EGG TRAY

Walter H. Randall, Waterville, Maine, assignor to Keyes
Fibre Company, Portland, Maine, a corporation of Maine

Filed Oct. 2, 1962, Ser. No. 71,962

Term of patent 14 years

(Cl. D58—13)

FIG. 1 is a top plan view of an egg tray embodying my new design;

FIG. 2 is a cross-sectional view along the line 2—2 of FIG. 1; and

FIG. 3 is a cross-sectional view along the line 3—3 of FIG. 1.

I claim:

The ornamental design for an egg tray, as shown and described.
